(57) **ABSTRACT**

A folding knife including a handle, a pivot axis, and a blade having a cutting edge. The blade is pivotably coupled to the handle such that the blade is pivotable relative to the handle about the pivot axis between a retracted position and an extended position. The cutting edge is exposed in the extended position and a portion of the blade is received within the handle in the retracted position. The folding knife further includes a bearing assembly for facilitating movement of the blade between the retracted position and the extended position. The bearing assembly includes a first bearing recessed within the blade and a second bearing recessed within the handle.

**CROSS-REFERENCE TO RELATED
APPLICATIONS**

This application is a continuation of U.S. application Ser. No. 15/373,071, filed Dec. 8, 2016, which claims the benefit of and priority to U.S. Provisional Patent Application No. 62/265,487, filed Dec. 10, 2015, the entire contents of each of which are incorporated by reference.

BACKGROUND

The present invention relates to knives and more particularly to folding knives.

SUMMARY

In one embodiment, the invention provides a folding knife including a handle, a pivot axis, and a blade having a cutting edge. The blade is pivotably coupled to the handle such that the blade is pivotable relative to the handle about the pivot axis between a retracted position and an extended position. The cutting edge is exposed in the extended position and a portion of the blade is received within the handle in the retracted position. The folding knife further includes a bearing assembly for facilitating movement of the blade between the retracted position and the extended position. The bearing assembly includes a first bearing recessed within the blade and a second bearing recessed within the handle.

In another embodiment, the invention provides a folding knife including a first handle portion, a second handle portion coupled to the first handle portion, a pivot axis, and a blade having a cutting edge. The blade is pivotably coupled to the handle between the first handle portion and the second handle portion. The blade is pivotable about the pivot axis between a retracted position and an extended position. The cutting edge is exposed in the extended position and a portion of the blade is received within the handle in the retracted position. The folding knife further includes a bearing coupled to the second handle portion for facilitating movement of the blade between the retracted position and the extended position. The bearing includes a bearing cage and a plurality of balls partially supported by the bearing cage. The blade and the second handle portion act as a bearing race to partially support the plurality of balls of the bearing.

In another embodiment, the invention provides a folding knife including a first handle portion, a second handle portion coupled to the first handle portion, a pivot axis, and a blade having a cutting edge. The blade is pivotably coupled to the handle between the first handle portion and the second handle portion. The blade is pivotable about the pivot axis between a retracted position and an extended position. The cutting edge is exposed in the extended position and a portion of the blade is received within the handle in the retracted position. The folding knife further includes a bearing coupled to the blade for facilitating movement of the blade between the retracted position and the extended position. The bearing includes a bearing cage that is recessed within the blade. The bearing further includes a plurality of balls that extend beyond the blade to form a gap between the blade and the first handle portion.

Other aspects of the invention will become apparent by consideration of the detailed description and accompanying drawings.

2
BRIEF DESCRIPTION OF THE DRAWINGS

FIG. 1 is a perspective view of a knife according to an embodiment of the invention.

5 FIG. 2 is an exploded perspective view of a back side of the knife of FIG. 1.

FIG. 3 is an exploded perspective view of a front side of the knife of FIG. 1, illustrating a portion of a bearing assembly disposed about a rotational axis of the knife.

10 FIG. 4 is a perspective view of the bearing assembly.
FIG. 5 is a cross-sectional view of the knife along line 5-5 of FIG. 2.

15 Before any embodiments of the invention are explained in detail, it is to be understood that the invention is not limited in its application to the details of construction and the arrangement of components set forth in the following description or illustrated in the following drawings. The invention is capable of other embodiments and of being practiced or of being carried out in various ways.

DETAILED DESCRIPTION

FIGS. 1 and 2 illustrate a knife, and more specifically, a folding knife 10. The knife 10 includes a first handle portion 14, a second handle portion 18, and a blade 22 pivotally coupled to the handle portions 14, 18. The handle portions 14, 18 each generally define half of a handle 30 of the knife 10. The blade 22 is pivotally coupled to the handle 30 so that the blade 22 can pivot about a pivot axis 34 between an extended position (FIG. 1) and retracted or closed position (FIG. 2). In the retracted position, a portion of the blade 22 is received and stored within the handle 30 between the portions 14, 18. The handle 30 includes a blade cavity 38 adjacent a front side 39 of the handle 30 that receives at least 30 a portion of blade 22 in the retracted position. The blade cavity 38 is disposed between the handle portions 14, 18.

35 With continued reference to FIGS. 1 and 2, the blade 22 includes a tang 42 proximate the pivot axis 34 and a distal end 46 located opposite the tang 42. The blade 22 further 40 includes a cutting edge 50 formed by opposing faces 54, 58 of the blade 22 converging toward each other to a common apex. The cutting edge 50 of the blade 22 is configured to be used by an operator to perform a cutting operation. Although 45 the cutting edge 50 of the illustrated embodiment is partially serrated, in other embodiments, the cutting edge 50 may be formed differently (i.e., a continuous edge).

The blade 22 further includes a protruding portion (i.e., an actuator 62) proximate the tang 42. The actuator 62 is 50 formed as an integral member of the blade 22 and protrudes outwardly from the tang 42. Specifically, the actuator 62 extends beyond an outer periphery 63 of the handle 30 in the extended and retracted position of the blade 22. As a result, an operator has access to the actuator 62 when the blade 22 is in the retracted position. Although the actuator 62 of the 55 illustrated embodiment is integrally formed with the blade 22, the actuator 62 may alternatively be a separate component from the blade 22 such that the blade 22 pivots in response to the actuator 62 acting on a portion of the blade 22, e.g. a kicker that is rotatable separate from the blade 22 and is configured to act on the blade 22 to open the blade 22.

60 With reference to FIGS. 1-3, the knife 10 of the illustrated embodiment further includes a spacer 82 interposed between the handle portion 18 and a liner 114. The liner 114 is, in turn, interposed between the handle 14 and the blade 22. A 65 plurality of fasteners 78 connects the spacer 82, the liner 114, and the handle portions 14, 18. The spacer 82 is disposed proximate the rear end of the knife 10 and defines

a width of the blade cavity 38. The spacer 82 includes a stop surface 86 that abuts the blade 22 in the retracted position of the blade 22 to inhibit further rotation of the blade 22 beyond the retracted position.

In the illustrated embodiment of FIG. 2, the knife 10 further includes a locking arm 90 formed as an integral component of the handle portion 18. The locking arm 90 maintains the blade 22 in the extended position. The locking arm 90 is cantilevered from a portion of the handle portion 18. The locking arm 90 also has a free end 98 extending away from a connecting end 102. The locking arm 90 is curved such that the free end 98 is biased toward the blade cavity 38. The locking arm 90 is movable between a locked configuration and an unlocked configuration. In the locked configuration, the locking arm 90 inhibits movement of the blade 22. In the unlocked configuration, movement of the blade 22 is allowed. The locking arm 90 is biased toward the locked configuration, in which the free end 98 of the locking arm 90 engages a shoulder 106 at the tang 42 of the blade 22 to resist movement of the blade 22 away from the extended position. The free end 98 of the locking arm 90 includes a tab 110 that is partially disposed outside of the handle 30 to enable an operator to easily access the tab 110. The tab 110 facilitates moving the locking arm 90. A retaining member (i.e., a washer 118 and a fastener 122) is secured to the handle portion 18 and selectively engages the locking arm 90. Specifically, the washer 118 engages the locking arm 90 when the locking arm 90 is actuated toward the unlocked configuration in order to inhibit the locking arm 90 from extending beyond the unlocked configuration. Also, the washer 118 avoids inadvertent or excessive bending of the locking arm 90, which could cause the knife 10 to malfunction.

With reference to FIGS. 2-4, the knife 10 further includes a bearing assembly 126 disposed about the pivot axis 34 to facilitate rotational movement of the blade 22 relative to the handle portions 14, 18. Specifically, the handle portions 14, 18, the liner 114, and the blade 22 each include an aperture 128 co-axial with the pivot axis 34 for receiving at least a portion of the bearing assembly 126. The bearing assembly 126 includes a first or male fastener 130 (i.e., screw, bolt, etc.) and a second or female fastener 134 (i.e., screw, bolt, etc.) that couple together in order to pivotally couple the handle portions 14, 18 and the blade 22. The male fastener 130 includes a head 138, a tool receiving portion 142 on the head 138, and an externally threaded stem 146 protruding away from the head 138. Similarly, the female fastener 134 includes a head 150, a tool receiving portion 154 (FIG. 5) on the head 150, and an internally threaded stem 158 protruding away from the head 138. The internally threaded stem 158 has the inverse thread pattern to that of the externally threaded stem 146, such that the stem 146 is threadable and thereby receivable with stem 150. As shown in the illustrated construction of FIG. 4, the outer periphery of the stem 150 is cylindrical in shape, which engages the inner periphery of the apertures 128.

With reference to FIG. 5, when assembling the knife 10, the apertures 128 of the handle portions 14, 18, the liner 114, and the blade 22 are aligned in order to pass the female fastener 134 through the apertures 128 until the head 150 engages the handle portion 14. Subsequently, the male fastener 130 passes through the handle portion 18 to mate with the female fastener 134. At this point, at least one of the fasteners 130, 134 is rotated to cause the threaded portions 146, 158 to engage causing axial movement of the fasteners 130, 134 along the rotational axis 34 until each head 138, 150 engages the handle portions 18, 14, respectively, thereby

capturing the handle portions 14, 18, the liner 114, and the blade 22 between the heads 138, 150. The heads 138, 150 are low-profile in order to minimize the amount at which the fasteners 130, 134 protrude beyond a width W of the knife 10.

With reference to FIGS. 2-4, the bearing assembly 126 further includes a set of thrust bearings 162, 166 disposed co-axially with the axis 34 and about the female fastener 134 to minimize friction during relative movement between the handle portions 14, 18 and the blade 22. Like conventional rotary rolling-element bearings, the thrust bearings 162, 166 permit rotation between parts (e.g., the blade 22 and the liner 114). However, the thrust bearings 162, 166 also provide support to a load in a predominately axial direction (e.g., pivot axis 34). The thrust bearings 162, 166 are disposed on opposing sides of the blade 22 creating a gap 170 (FIG. 5) on either side of the blade 22 to inhibit contact between the opposing face 54 of the blade 22 and the liner 114, and the other opposing face 58 and the handle portion 18. Each thrust bearing 162, 166 includes a plurality of engagement members (e.g., balls 174) and a disc-shaped cage 178 having a plurality of apertures 182. Each thrust bearing 162, 166 further includes inner and outer circumferential flanges 186 that extend away from the disc-shaped cage 178. The balls 174 are radially constrained by the inner and outer circumferential flange 186. Also, the balls 174 are axially constrained at least partially by the apertures 182 of the disc-shaped cage 178. The balls 174 are further constrained in the axial direction by the blade 22 and the liner 114. Specifically, the liner 114 and the blade 22 substantially act as a race for the thrust bearing 162 to further constrain the balls 174 in the axial direction of axis 34. Also, the blade 22 and the handle portion 18 substantially act a race of the thrust bearing 166 to further constrain the balls 174 in the axial direction of axis 34. Eliminating the race as being an integral member of the thrust bearings 162, 166 advantageously decreases the width W of the knife 10 for ease of storage in the user's pocket, tool belt, knife holster, or the like. Although the bearing 166 of the illustrated embodiment is disposed within the handle 18, in other embodiments, the bearing 166 may alternatively be disposed within the blade 22 such that both bearings 162, 166 are disposed within the blade 22.

With reference to FIG. 5, when the knife 10 is assembled, the thrust bearing 162 is recessed within an annular inwardly-extending groove 190 (i.e., a pocket) formed on the blade 22, whereas the thrust bearing 166 is recessed within an annular inwardly-extending groove 194 (i.e., a pocket) formed on the handle portion 18. As such, the disc-shaped cage 178 of each bearing 162, 166 is encased within each groove 190, 194, respectively. That is, the thrust bearing 162 is coupled to the blade 22 and the thrust bearing 166 is coupled to the handle portion 18. The balls 174 of the thrust bearing 162 extend beyond the opposing face 54 of the blade 22 to form the gap 170 between the blade 22 and the liner 114. Similarly, the balls 174 of the thrust bearing 166 extend beyond the handle portion 18 to form the gap 170 between the blade 22 and the handle portion 18.

In operation, to pivot the blade 22 from the retracted position to the extended position, an operator applies a force 60 to the actuator 62. Once the blade 22 is in the extended position, the locking arm 90 engages the shoulder 106 of the blade 22. To pivot the blade 22 from the extended position to the retracted position, an operator applies a force to a portion of the blade 22, while simultaneously moving the locking arm 90 from the locked configuration to the unlocked configuration. While the blade 22 pivots between the retracted and extended positions, the plurality of balls

5

174 of the thrust bearing 162 engage with and roll against the groove 190 of the blade 22 and the liner 114. Also, the plurality of balls 174 of the thrust bearing 166 engage with and roll against the groove 194 of the handle portion 18 and the opposing face 58 of the blade.

Although the invention has been described in detail with reference to certain preferred embodiments, variations and modifications exist within the scope and spirit of one of more independent aspects of the invention as described.

What is claimed is:

1. A folding knife comprising:

a handle including a first handle and a second handle coupled to the first handle;

a pivot axis;

a blade having a cutting edge, the blade is pivotably coupled to the handle between the first handle and the second handle, the blade comprising an annular inwardly-extending groove, the blade is pivotable about the pivot axis with respect to the first handle and the second handle between a retracted position and an extended position, the cutting edge is exposed in the extended position and a portion of the blade is received within the handle in the retracted position; and

a bearing within the annular inwardly-extending groove in the blade for facilitating movement of the blade between the retracted position and the extended position, the annular inwardly-extending groove comprising a recessed surface facing towards the first handle, the bearing including a disc-shaped bearing cage and a plurality of balls partially supported by the disc-shaped bearing cage, the disc-shaped bearing cage comprising a lateral surface that faces towards the first handle and away from the recessed surface; and

a stem that extends longitudinally along the pivot axis, the stem comprising an outer surface comprising a planar portion, wherein the planar portion extends longitudinally along the pivot axis and faces away from the pivot axis, and the planar portion of the outer surface of the stem is received within an aperture of the second handle and an aperture of the bearing.

2. The folding knife of claim 1, the outer surface of the stem comprising a cylindrical outer surface that extends longitudinally along the pivot axis and faces away from the pivot axis.

3. The folding knife of claim 1, further comprising:

a second annular inwardly-extending groove in the second handle; and

a second bearing within the second annular inwardly-extending groove, the second bearing including a second disc-shaped bearing cage and a second plurality of balls partially supported by the disc-shaped bearing cage.

4. The folding knife of claim 3, wherein the stem comprises an internal threading.

5. The folding knife of claim 1, wherein the plurality of balls extend beyond the blade to form a gap between the blade and the first handle.

6. The folding knife of claim 1, wherein the first handle and the second handle are detachably coupled.

7. The folding knife of claim 1, wherein the disc-shaped bearing cage does not extend out of the annular inwardly-extending groove.

6

8. A folding knife comprising:

a handle including a first handle and a second handle coupled to the first handle; a pivot axis;

5 a blade having a cutting edge, the blade is pivotably coupled to the handle between the first handle and the second handle, the blade is pivotable about the pivot axis with respect to the first handle and the second handle between a retracted position and an extended position, the cutting edge is exposed in the extended position and a portion of the blade is received within the handle in the retracted position;

10 an annular inwardly-extending groove in the second handle;

15 a bearing within the annular inwardly-extending groove in the second handle, the bearing including a disc-shaped bearing cage and a plurality of engagement members partially supported by the disc-shaped bearing cage; and

20 a stem that extends longitudinally along the pivot axis, the stem comprising a planar outer surface that extends longitudinally along the pivot axis and faces away from the pivot axis, the planar outer surface of the stem is received within an aperture of the blade and an aperture of the bearing.

25 9. The folding knife of claim 8, the plurality of engagement members comprising a plurality of balls.

10. The folding knife of claim 8, the stem comprising an outer surface that comprises the planar outer surface and a cylindrical outer surface, each of which extend longitudinally along the pivot axis.

11. The folding knife of claim 8, wherein the disc-shaped bearing cage does not extend out of the annular inwardly-extending groove.

12. The folding knife of claim 8, wherein the stem comprises an internal threading.

13. The folding knife of claim 12, wherein the first handle and the second handle are detachably coupled.

14. The folding knife of claim 8, wherein the plurality of engagement members extend beyond the second handle to form a gap between the second handle and the blade.

15. A folding knife comprising:

a handle including a first handle and a second handle coupled to the first handle;

50 a pivot axis;

a blade having a cutting edge, the blade is pivotably coupled to the handle between the first handle and the second handle, the blade is pivotable about the pivot axis with respect to the first handle and the second handle between a retracted position and an extended position, the cutting edge is exposed in the extended position and a portion of the blade is received within the handle in the retracted position; and

55 a first annular inwardly-extending groove in the blade; a first bearing within the first annular inwardly-extending groove in the blade, the first bearing defining a first central aperture, the first bearing comprising a first plurality of engagement members arranged around the first central aperture, the first plurality of engagement members facilitating movement of the blade between the retracted position and the extended position;

60 a second annular inwardly-extending groove in the second handle;

65 a second bearing within the second annular inwardly-extending groove in the second handle, the second bearing defining a second central aperture, the second bearing comprising a second plurality of engagement members arranged around the second central aperture, the second plurality of engagement members facilitating movement of the blade between the retracted position and the extended position;

members arranged around the second central aperture, the second plurality of engagement members facilitating movement of the blade between the retracted position and the extended position; and a stem received within the first central aperture of the first bearing and the second central aperture of the second bearing, the stem comprising a planar outer surface that faces towards at least one of the first bearing and the second bearing.

16. The folding knife of claim **15**, the first plurality of engagement members comprising a first plurality of balls, and the second plurality of engagement members comprising a second plurality of balls.

17. The folding knife of claim **15**, the stem comprising an outer surface that comprises the planar outer surface and a cylindrical outer surface, each of which extend longitudinally along the pivot axis.

18. The folding knife of claim **15**, the first bearing comprising a first disc-shaped bearing cage that supports the first plurality of engagement members, the second bearing comprising a second disc-shaped bearing cage that supports the second plurality of engagement members.

19. The folding knife of claim **18**, wherein the first disc-shaped bearing cage does not extend out of the first annular inwardly-extending groove, and the second disc-shaped bearing cage does not extend out of the second annular inwardly-extending groove.

20. The folding knife of claim **15**, wherein the first plurality of engagement members extend beyond the blade to form a gap between the blade and the first handle, and the second plurality of engagement members extend beyond the second handle to form a gap between the second handle and the blade.
